(57) **CLAIM**

The ornamental design for a ventilated carafe lid with spout, as shown and described.

DESCRIPTION

FIG. 1 is a bottom perspective view of a ventilated carafe lid with spout, showing the new design.

FIG. 2 is a rear view thereof.

FIG. 3 is a front view thereof.

FIG. 4 is a left side view thereof.

FIG. 5 is a right side view thereof.

FIG. 6 is a bottom view thereof.

FIG. 7 is a top view thereof; and,

FIG. 8 is a front perspective view thereof in a condition of use.

The broken lines in the drawings depict portions of the ventilated carafe lid with spout that form no part of the claimed design.
